UNITED STATES PATENT OFFICE.

SAMUEL F. BURGESS, OF WEST MORRIS, CONNECTICUT.

CLOTHES-FRAME.

SPECIFICATION forming part of Letters Patent No. 376,580, dated January 17, 1888.

Application filed July 8, 1887. Serial No. 243,767. (No model.)

To all whom it may concern:

Be it known that I, SAMUEL F. BURGESS, of West Morris, in the county of Litchfield and State of Connecticut, have invented a new and 5 Improved Clothes-Frame, of which the following is a full, clear, and exact description.

My invention relates to a folding clothes-frame; and it consists, principally, of two central braces connected to the upper ends of the 10 end uprights of the frame, and connected, also, at their adjacent ends to a central brace for spreading apart and bracing the center uprights.

The invention also consists of the construction, arrangement, and combination of parts, 15 all as hereinafter described and claimed.

Reference is to be had to the accompanying drawings, forming a part of this specification, in which similar letters of reference indicate 20 corresponding parts in both figures.

Figure 1 is a perspective view of my improved clothes-frame extended for use, and Fig. 2 is a side elevation of the same folded.

A A and B B represent the end uprights of 25 the clothes-frame, and C C represent the central uprights. The uprights A are connected together at their upper ends by the U-shaped wire a, on which they are hinged.

The uprights A A are also connected together 30 by the flexible tapes or strips b, to prevent spreading too far, and said uprights are connected to the central uprights, C, by several pivoted cross-pieces D D, in the ordinary manner. The end uprights, B B, are in like manner connected together by the U-shaped hinge-wire c and tape or strap d, and are connected to the opposite side of the central uprights, C, by the hinged cross-pieces E E, corresponding in number and position to the cross-pieces D. 35

40 To the hinge-rods a c, between the end up-

rights, are connected the outer ends of the central braces, F. The inner adjacent ends of these braces are connected by a U-shaped wire, f, and on the wire between the ends of the braces F is placed the center brace, G, which 45 is adapted to be turned upon the wire f to bring it to horizontal position, as shown in Fig. 1, or to vertical position, as shown in Fig. 2. When in the latter position, the whole frame may be folded to the position shown in Fig. 2. 50 When the frame is opened out to the position shown in Fig. 1 for use, the brace G is to be turned to horizontal position and its ends inserted in small sockets made in the central uprights, C, so that it spreads and forms a lateral 55 brace for the central uprights, and also forms a base for the inner ends of the braces F, which in turn brace the frame endwise.

When the frame is folded, the brace G is turned to vertical position, and the braces F 60 fold in between the end uprights, A B, as shown clearly in Fig. 2.

Having thus fully described my invention, what I claim as new, and desire to secure by Letters Patent, is—

1. The combination, with the end uprights, A B, and central upright, C, connected together by cross-pieces D E, of the braces F, connected to the upper end of the end upright and to the central brace, G, substantially as 70 and for the purposes set forth.

2. In a clothes-frame, the center braces connected at their outer ends to the joined ends of the end uprights and connected at their inner ends by the wire f, on which the brace G 75 is pivoted, substantially as described.

SAMUEL F. BURGESS.
